UNITED STATES PATENT OFFICE.

PHILIP PENDLETON, OF BATH, WEST VIRGINIA, ASSIGNOR OF ONE-HALF
TO JAMES W. DENVER, OF WILMINGTON, OHIO.

RAILROAD-TIE.

SPECIFICATION forming part of Letters Patent No. 255,392, dated March 21, 1882.

Application filed July 14, 1881. (No model.)

To all whom it may concern:

Be it known that I, PHILIP PENDLETON, of Bath, in the county of Morgan and State of West Virginia, have invented certain Improvements in Railroad-Ties; and I hereby declare the following to be a full, clear, and exact account thereof, reference being had to the accompanying drawings, making part of this specification, in which—

10 Figure 1 is a perspective view of the tie and sections of rail. Fig. 2 is a longitudinal sectional view. Figs. 3, 4, 5, and 6 are details to be referred to.

The object of my invention is to provide a 15 railroad-tie which will have great endurance and comparatively a low cost.

My invention consists of a certain combination and arrangement of devices, as hereinafter more fully described and claimed.

20 In order that those skilled in the art may make and use my invention, I will proceed to describe the manner in which I have carried it out.

In the said drawings, A is the tie-bar, made 25 of forged, rolled, or cast metal, and provided with flaring ends. On each end of the tie-bar are secured by means of broad dovetail grooves a boxes B B, having their sides contiguous to the outer ends of the tie-bar curved, as seen at 30 b, and formed into hook-shaped sockets d d, to receive one edge of the flanges e of the rails D.

Within the boxes B B are placed blocks E, of some non-rigid, yielding, or semi-elastic material, preferably wood, to form seats, upon 35 which rest the bottoms of the flanges of the rails. A binding-plate, P, lies upon each block E, and has its edge i resting on the flange e of rail D. At each end of the tie a bolt, o, passes through tie-bar, box B, block E, and binding-plate P,

and secures them all together, and through the 40 medium of plate P binds the rail down on block E.

It is evident that the blocks E may be made of any material which sufficiently lacks rigidity to take up, or partially take up, the jar on 45 the rails when trains are passing without departing from the spirit of my invention. The blocks, being easily removable, when worn, can be easily replaced without removing the rail, except from the particular tie containing the 50 block to be changed.

For convenience I may prefer to slot the ends of the blocks, as seen at n, instead of boring them, to receive the bolt o. This construction 55 enables me to remove the blocks and replace them without removing the binding-plates by simply loosening up the nut p and sliding the block into the box from the outside of the rails.

I find it desirable to contract the width of the tie-bar A toward the center, because it is 60 an economy of metal, and no material width of the bar is necessary at the center to withstand any tensile strain that may be put upon it; but the same can be made of any size or shape or weight deemed necessary to secure 65 the requisite strength.

Having thus described my invention, what I claim as new, and desire to secure by Letters Patent, is—

The combination and arrangement of the tie-bar A, removable boxes B B, blocks E, binding-plates P P, bolts o, and rails D, substantially as and for the purpose set forth.

PHILIP PENDLETON.
